UNITED STATES PATENT OFFICE.

CHARLES FRANCOIS ALFRED CHAPITEL, OF NANTES, FRANCE.

CRUSHING AND MIXING MACHINE.

998,840.

Specification of Letters Patent. Patented July 25, 1911.

Application filed December 20, 1910. Serial No. 598,368.

To all whom it may concern:

Be it known that I, CHARLES FRANCOIS ALFRED CHAPITEL, a citizen of the French Republic, and residing at Nantes, France, have invented certain new and useful Improvements in Crushing and Mixing Machines, of which the following is a specification.

My invention relates to crushing and mixing machines having swinging hammers which revolve with great speed within a stationary casing, the casing being surrounded with a slowly revolving drum screen, provided with buckets on its inner surface adapted to convey the unscreened material to an opening in the casing above the hammers.

In describing the invention reference will be had to the accompanying drawings where- 20 in like characters of reference denote corresponding parts in the several views, and in which:—

Figure 1 is a vertical section of the device. Fig. 2 is a vertical section at right angles to 25 that shown in Fig. 1. Fig. 3 is a sectional view of one of the hammers employed in the device. Fig. 4 is a plan view of a portion of the screen. Figs. 5 and 6 are sectional views of a modification of the device.

The improved crushing and mixing machine comprises a fixed casing composed of two side cheeks *a* either united by cross bolts, or may be cast integral with a section of the shell or peripheral wall of the cylinder casing *b*. The said casing has an opening *c* in 35 its upper end to receive the material coming from the screen and an opening *d* in its lower end through which the material passes to the screen. In the side walls of the casing 40 are openings *f*, into which lead the pipes or conduits *e* conveying the material to be reduced. Suitably mounted in the bearings *p*, on the plates *o*, which as shown are cast in one piece with the side cheeks *a*, is the shaft *g*.

The said shaft carries within the casing a sleeve *g** which is recessed so as to form a 45 series of parallel disks or arms *h* to which the hammers *k* are pivotally connected by means of the rods *l*. A pulley *m*, secured to the shaft *g*, transmits motion to the same. In the upper end of the casing are arranged the screens *n*, so as to receive material rebounding from the wall of the casing. Two doors *q* in the end walls of the cylinder 55 permit easy access to the interior of the casing. The side cheeks *a* of the casing

terminate in rails *r* upon which runs the sleeve drum.

The sifting drum is composed of two ends or crowns *s* united by partitions *t* which 60 form a bucket chain. On the outer surface of each of the crowns *s* a series of rollers *u* are arranged which serve for carrying the drum. The sieve *v* which forms the peripheral wall of the drum is composed of a number 65 of sections of perforated sheet metal or wire gauze fixed upon a frame so that they can be easily removed. Said frames are fixed upon the rims of the crown *s*. The drum carries at the middle of its periphery a ring 70 or band *x* which serves as a driving pulley for the drum. The sifting is completed by grates *y*, *z* arranged in the cylinder so that they receive the material before it passes out of the lower portion of the device. 75

The operation of the machine is as follows:—The shaft *g* with its hub *h* is rotated at a high speed so that the hammers *k* are moved toward the periphery of the cylinder. The drum is revolved simultaneously at slow speed. The materials entering the openings *c* fall upon the moving hammers *k* whereby they are crushed and broken as well by the direct strokes of the hammers as by the ricochet motion which 85 throws them against the screens *n*. The material is submitted to this treatment until it is crushed into particles which are small enough to fall through the sieves *v*. The refuse from the sieves is collected by the 90 buckets *t* and poured again into the cylinder through the opening *c*.

The advantages of this machine are that a minimum of waste is produced as the hammers act only in an upward direction, 95 that is to say break the material instead of crushing the same. There could further be superposed several series of sieves in order to obtain a simultaneous sifting of several sorts of grain. 100

It is evident that the construction of the machine could be modified within the limits of this invention. The sifting drum could for example have different sieves superposed; the hammers (Fig. 3) could be 105 mounted in the hub by means of one or more hinge joints; the head of the hammer (Fig. 3) could have several teeth or cutters and the screens (Fig. 4) could form combs between the prongs of which the teeth of the 110 hammers can pass; the inner walls of the fixed cylinder could be reinforced and

strengthened by undulated plates of hard metal. The rollers which carry the sifting drum can be mounted in the cheeks *a* of the casing (Fig. 5) in which case the drum 5 would run directly upon said rollers. In this case the drum would be driven from the shaft *g* by means of a belt transmission 2 which is connected with the shaft 3 of one of the rollers.

10 I claim:—

An improved crushing and mixing machine comprising in combination, a fixed cylinder having inlet openings in its end walls for the material to be treated, one inlet 15 opening at the upper end and an outlet opening at the lower end, impact plates arranged in the cylinder below the inlet open-

ings, a transverse shaft revolvably mounted in the end walls, arms mounted upon the said shaft and swinging hammers mounted 23 between said arms so that they swing outward when the shaft revolves, a sifting drum surrounding said cylinder, means for slowly revolving said sifting drum, and buckets in said sifting drum, substantially 25 as described and shown and for the purpose set forth.

In witness whereof I have hereunto set my hand in the presence of two witnesses.

CHARLES FRANÇOIS ALFRED CHAPITEL.
